US00D864195S

(12) **United States Design Patent** (10) **Patent No.:** **US D864,195 S**
Wei (45) **Date of Patent:** **** Oct. 22, 2019**

(54) **GRAPHIC TABLET**

(71) Applicant: **Luo Wei**, Guangdong (CN)
(72) Inventor: **Luo Wei**, Guangdong (CN)
(73) Assignee: **SHENZHEN HUION ANIMATION TECHNOLOGY CO. LTD.**, Shenzhen, Guangdong (CN)

(**) Term: **15 Years**

(21) Appl. No.: **29/576,738**

(22) Filed: **Sep. 7, 2016**

(51) **LOC (12) Cl.** **14-02**
(52) **U.S. Cl.**
USPC **D14/341**

(58) **Field of Classification Search**

USPC ..... D14/341-347, 420, 426, 129-130, 496, D14/138, 138 G, 138 R, 138 AA, 138 AB, D14/138 C, 139, 248, 203.1-203.8, D14/388-389, 140-142, 374, 356, 257, D14/299, 358, 137, 240, 129-130; D10/104.4, 65; D21/324, 329, 332
